UNITED STATES PATENT OFFICE.

HENRY E. MAURER, JR., OF SPRINGFIELD, ILLINOIS, ASSIGNOR OF ONE-HALF TO
HARRY L. IDE, OF SPRINGFIELD, ILLINOIS.

JACK.

1,288,103.

Specification of Letters Patent. Patented Dec. 17, 1918.

Application filed April 24, 1918. Serial No. 230,427.

To all whom it may concern:

Be it known that I, HENRY E. MAURER, Jr., a citizen of the United States, residing at Springfield, in the county of Sangamon 5 and State of Illinois, have invented a certain new and useful Improvement in Jacks, of which the following is a full, clear, concise, and exact description.

My invention relates to jacks used for 10 lifting or otherwise moving objects. The jack of my invention is of particular use in compressing the springs employed in the operation of puppet valves in order that the valves may readily be removed and cleaned, 15 ground, or reseated, though the invention is not to be limited to this use.

My invention has for one of its objects 20 the provision of a construction whereby a jack may readily be applied to valves or other objects of different locations and environments which hitherto required jacks of different designs adaptable to the varying work. The jack of my invention enables 25 me to operate in cramped spaces which would not accommodate jacks with oscillating ratchet members.

The invention has for another object the provision of a construction whereby the effective length or height of a jack may be 30 adjusted to suit the locality where it is employed. In carrying out the first object of my invention I construct the jack with a rod, a load engaging element supported by the rod, a member projecting from the rod 35 and movable with the load engaging element longitudinally of the axis of the rod and angularly adjustable with respect to the load engaging element, and mechanism co-acting with the rod for effecting movement of said 40 load engaging element and member longitudinally of the rod axis and including an actuating element movable with respect to and bodily with said member and operable with the load engaging element and member 45 in relatively fixed positions.

In carrying out the second object of my invention a base that carries the rod is movable longitudinally of the rod, being preferably threaded upon the rod, the rod desirably passing through the base whereby 50 the effective height or length of the jack (which is measured between the base and one end of the rod) may readily be adjusted.

I will explain my invention more fully by 55 reference to the accompanying drawing

showing the preferred embodiment thereof and in which Figure 1 is a view showing the jack of my invention partially broken away and adjusted in position to lift a spring abutment or washer at the lower end 60 of a valve spring, a position to which the jack is adjusted to lift the washer being indicated by dotted lines; Fig. 2 is a longitudinal sectional view of the jack; and Fig. 3 is a sectional view on line 3—3 of 65 Fig. 2, an alternative position of a fork member of the jack and the parts carried thereby being indicated by dotted lines.

Like parts are indicated by similar characters of reference throughout the different 70 figures.

The drawing illustrates one use to which the jack may be put, Fig. 1 showing a portion 1 of a cylinder and a part 2 of the removable cylinder head. The valve 3 may be 75 either an inlet or an exhaust valve, this valve having a seat 4 in the engine cylinder. The usual valve stem 5 projects downwardly from the valve 3 and through the valve stem guide 6 carried by the engine cylinder. An 80 abutting washer 7 is assembled with the stem 5 at the lower end of the stem by means of the usual key 8 passing through a transverse hole in the stem. The valve spring 9 is in abutting engagement, at its upper end, with 85 the guide structure 6 and at its lower end with the washer 7, the key 8 limiting the extent to which the washer may be depressed by the spring and being so located as to maintain the spring under compression. 90 The washer may be moved, upon the application of sufficient lifting force, along the stem and away from the key 8.

The jack structure illustrated includes a threaded rod 10 and a base 11 that carries 95 the rod. This base is preferably of fork shape so that it may readily straddle the nut 12 that is employed to clamp the post 13 in engagement with the plunger 14 whereby the base may be firmly seated upon the plunger guiding portion of the engine cylinder structure. The portion or branch 15 of a fork or oscillating member 16 carries a sleeve 17. The other branch 18 of this fork carries a sleeve 19. These sleeves are aligned 105 and the rod passes freely therethrough whereby the fork is journaled on and is movable along said rod. The load supporting member is preferably in the nature of an arm 20 that has two substantially parallel 110

branches 21, 22 which respectively surround the sleeves 17 and 19 that have bearing engagement with said branches whereby said fork may be swung to different angles respecting said arm and, as the sleeves are free of threaded engagement with the rod so that the fork may be freely movable longitudinally of the rod, the fork will follow the movements of the arm without disturbing the angular selected adjustment of the fork with respect to the arm. An alternative angular position of the fork and parts carried thereby is indicated by dotted lines in Fig. 3. The two branches 21 and 22 prevent the arm from being tilted with respect to the rod 10. Said arm is preferably of fork shape at its outer and work-engaging end where it is alined with the forked end of the base 11. By making this end of the arm fork-shaped it may readily straddle the valve stem and clear the key 8 whereby the arm may have direct lifting engagement with the spring engaging washer 7 to be able to effect the movement of this washer away from the key. The bevel pinion 23 is interposed between the branches 15 and 18 of the fork 16 and is in threaded engagement with the rod 10, the top face of this pinion being in thrusting engagement with the inner face of the branch 15 whereby the fork 16 and the arm 20 are elevated when the pinion 23 is moved upwardly.

In order to prevent the threads in the pinion 23 from stripping, this pinion desirably has an elongated hub 23¹ in which the threads of the pinion are continued. This hub desirably extends substantially into contact with the inner face of the branch 18 of the fork 16 to prevent the said pinion from having binding engagement with the second or actuating bevel pinion 24 which is also disposed between the branches of the fork 16 in position to be in mesh with the first pinion.

An operating shaft 25 is journaled in the stem 26 of the fork 16 and is brought into turning connection with the second pinion by means of a pin 27 passing through the shaft and the hub of this pinion. The outer end of the shaft may be provided with a wing head 28, a pin 29 holding the wing head and shaft in fixed relation. The two pins 27 and 29 preserve a fixed space between the pinion 24 and the head 28, the stem of the fork 16 being snugly received in this space but without binding engagement with said pinion and head. When the jack is initially inserted in the position illustrated by full lines in Fig. 1 the head 28 is turned in a direction to effect elevation of the arm 20 whereby the washer 7 is lifted away from the key 8 whereafter this key may readily be withdrawn to permit removal of the valve, which removal may be effected, where the removable cylinder head

2 is employed, after such cylinder head has been removed. After the valve has been removed and attended to, the arm 20 remaining in its elevated position, the valve may readily be replaced and the key 8 reinserted whereafter said arm 20 is lowered by reverse rotation of the wing head 28. If the opening 30 in the engine cylinder structure, through which opening the jack is to be inserted to apply it to the valve washer, is not so located as to permit the fork 16 to occupy the position with respect to the arm 20 indicated by full lines in the drawing, the fork may be swung around to occupy any other position with respect to this arm to suit the location of such opening, another alternative position of this fork and the parts carried thereby being indicated in Fig. 3. After the desired angular adjustment of the fork with respect to the arm has been secured, the jack is operated merely by turning the wing head and the shaft fixed with respect thereto upon an axis that is then fixed in one plane so that the jack may be manipulated in cramped spaces thereby possessing material advantage over jacks employing oscillating ratchet members that could not be employed in the same locations.

It will be observed that the forked end of the arm 20 is in the same plane with one of the branches of the arm thereby providing appreciable space between this forked end and the plane of the other branch. By this construction the arm and co-acting parts may be reversed in position upon the rod initially to adapt the jack to the space below the washer which varies in different makes of engines.

The rod 10 and the base 11 are desirably in threaded engagement, the rod passing through the base so that the distance between the base and the top of the rod may readily be adjusted to regulate the effective height of the jack whereby the length of the jack may be adjusted to have it insertible within different spaces. A set nut 31 serves to clamp the base in the position to which it is adjusted along the rod. While this feature of my invention is embodied in a jack having the other details of construction set forth I do not wish to limit this feature of the invention to a jack having such other characteristics.

While I have herein shown and particularly described the preferred embodiment of my invention I do not wish to be limited to the precise details of construction shown as changes may readily be made without departing from the scope of the appended claims, but having thus described my invention I claim as new and desire to secure by Letters Patent the following:

1. A jack including a threaded rod, a fork having two branches each carrying a sleeve that is alined with the sleeve carried

by the other branch, said rod passing freely through said sleeves whereby the fork is journaled upon and is movable along said rod; a load engaging element supported by 5 the rod and having two branches with which said sleeves are in bearing engagement whereby said fork may be swung to different angles respecting said load engaging element; a bevel pinion interposed between the 10 branches of the fork and in threaded engagement with said rod and in thrusting engagement with a branch of said fork; a second bevel pinion between the branches of the fork and in mesh with the aforesaid pinion; and an operating shaft journaled in the 15 stem of the fork and in turning connection with the second bevel pinion.

2. A jack including a threaded rod; a fork having two branches each carrying a 20 sleeve that is alined with the sleeve carried by the other branch, said rod passing freely through said sleeves whereby the fork is journaled upon and is movable along said rod; a load engaging element supported by 25 the rod and in bearing engagement with said fork whereby said fork may be swung to different angles respecting said load engaging element; a bevel pinion interposed between the branches of the fork and in threaded engagement with said rod and in thrusting engagement with a branch of said fork; a second bevel pinion between the branches of the fork and in mesh with the aforesaid pinion; and an operating shaft 30 journaled in the stem of the fork and in turning connection with the second bevel pinion.

3. A jack including a threaded rod; a member having a portion carrying a sleeve, 40 through which sleeve said rod freely passes whereby said member is journaled upon and is movable along said rod; a load engaging

element supported by the rod and in bearing engagement with said member whereby said member may be swung to different 45 angles respecting said load engaging element, a bevel pinion in thrusting engagement with said portion of said member and in threaded engagement with said rod; a second bevel pinion in mesh with the aforesaid 50 pinion; and an operating shaft journaled in said member and in turning connection with the second bevel pinion.

4. A jack including a threaded rod; a load engaging element supported by the rod; a 55 member projecting from said rod, this member being freely movable longitudinally of the rod and in swinging relation to said load engaging element to permit of the angular adjustment of said member with respect to the load engaging element; a bevel pinion in thrusting engagement with said member and in threaded engagement with said rod; a second bevel pinion in mesh with the aforesaid pinion; and an operating 60 shaft journaled in said member and in turning connection with the second bevel pinion.

5. A jack including a rod; a load engaging element supported by the rod; a member projecting from the rod and movable with 70 the load engaging element longitudinally of the axis of the rod and angularly adjustable with respect to the load engaging element; and mechanism co-acting with the rod for effecting movement of said load engaging 75 element and member longitudinally of the rod axis and including an actuating element movable with respect to and bodily with said member and operable with the load engaging element and member in relatively 80 fixed positions.

In witness whereof, I hereunto subscribe my name this 20 day of April A. D., 1918.
